UNITED STATES PATENT OFFICE.

ARTHUR F. VAN DYCK, OF RYE, NEW YORK, ASSIGNOR TO RADIO CORPORATION OF AMERICA, A CORPORATION OF DELAWARE.

ELECTRICAL SYSTEM AND SIGNALING METHOD.

Application filed May 27, 1924. Serial No. 716,146.

My invention relates to electrical systems and specifically to radio receiving systems for the reception, detection and amplification of incoming signal oscillations employing 5 the autodyne method of producing beat oscillations.

In certain radio receiving systems of the prior art successfully employing the autodyne method of detecting and amplifying 10 continuous signal oscillations, reliance has been placed upon the use of some harmonic (usually the second) of oscillations produced by the oscillating tube at a fundamental frequency substantially lower than the frequency 15 of the incoming signal waves to produce some desired beat frequency. A concrete example of this is as follows: Suppose the incoming signal oscillations possess a frequency of 600 kilocycles and a beat frequency 20 of 40 kilocycles is desired. The oscillating tube is then arranged to oscillate at a fundamental frequency of say 320 or 280 kilocycles, the second harmonic, 640 or 560 kilocycles of these fundamental frequencies 25 respectively, being then combined with the incoming signal oscillations to produce the desired 40 kilocycle beats.

The use of the so-called second harmonic for producing beat oscillations possesses certain disadvantages which are as follows: The second harmonic possesses a lower amplitude than the fundamental and while the fundamental serves no useful purpose its presence adds to the voltage swings on the 30 grid of the oscillating tube resulting in corresponding plate current variations. Therefore, for a given amplitude of the second harmonic, heavier loads are placed on the oscillating tube owing to the influence of the fundamental than would exist if the fundamental 35 were employed for producing the beat oscillations.

The use of the so-called second harmonic also brings into the operating range of such 40 a system a large number of combinations of frequencies which are present when signal oscillations are received. The result is that signals are received and detected at a multiplicity of adjustments of the oscillating tube 45 frequency instead of at only two positions when the so-called full frequency, substantially equal to the frequency of the incoming signal oscillations, is employed. The multiplicity of adjustments naturally results

in great confusion to the operator when attempting to adjust the system for the detection of the desired signal oscillations; while simplicity of adjustment naturally results from the employment of full frequency (560 kilocycles or 640 kilocycles in the concrete 55 example given above).

Heretofore certain difficulties existed which precluded the successful employment of the so-called full frequency in certain autodyne reception and detection systems. 60 For example the oscillator grid circuit and antenna circuit are necessarily tuned to substantially the same frequency. The ordinary manipulation of the controls often brings them into exact resonance with each other. 65 This condition will rob the grid of the oscillating tube of the voltage swings of the incoming signal oscillations and in some cases will even stop the oscillator from producing the desired oscillations thereby resulting in the non-detection of the incoming signal waves and the consequent inoperativeness 70 of the system. The energy from the oscillator will also in some cases appear in the antenna and be radiated therefrom.

The means for coupling the first and second tubes and the means for tuning the grid of the second tube, which is the oscillator, are of necessity both in the grid circuit of the second tube and since both are tuned to 80 substantially the same frequency they naturally influence each other. Each acts as a trap or filter circuit for the other and prevents the necessary transfer of voltage from one to the other as desired. The results of 85 this are lessened sensitivity of the system and even inoperativeness when incoming signal oscillations of certain frequencies are received.

One of the principal objects of my invention is the employment of full frequency in autodyne systems for the reception and detection of signal oscillations with all the resulting advantages of simplicity of adjustment, decrease of the load on the oscillator 90 tube and other advantages which will appear in the course of the description of my invention.

Another principal object of my invention is to overcome the above difficulties in autodyne systems in order that so-called full frequency oscillations may be employed for combining with the signal oscillations to 100 105

produce the required beat frequency for detection and amplification.

Other objects and advantages of my invention will be evident from the following 5 description taken in connection with the accompanying drawings, in which:

Fig. 1 is a schematic diagram of a radio receiving system of the autodyne and reflexing type and

10 Fig. 2 is a schematic diagram of a radio receiving system employing autodyne, neutralizing and reflexing principles for the reception and detection of incoming signal oscillations.

15 Referring to Fig. 1 the terminals of loop antenna 20 are connected to the grid and filament of a three-element thermionic device or tube 21 and a variable condenser 22 is connected across the terminals of the loop 20 antenna for tuning the same to the incoming signal waves. The plate of thermionic device 21, which functions as a radio frequency amplifier, is connected to the grid of the combined oscillating and detecting 25 three-element thermionic device or tube 23 through a small blocking condenser 24' for preventing the impression of the B-battery voltage of the plate-filament circuit of tube 21 on the grid element of tube 23.

30 An inductance coil 24 is connected across the grid and filament of tube 23, a variable tuning condenser 25 being connected in shunt with the coil. The plate-filament circuit of tube 23 comprises its battery B_1 , the 35 primary winding 26^p of intermediate frequency transformer 26 and a tickler coil 27 inductively coupled to the inductance coil 24, the battery B_1 with primary winding 26^p of intermediate frequency transformer 26 40 and the tickler coil 27 all being connected in series.

45 A condenser 28 is shunted across the primary winding of transformer 26 for bypassing undesired high frequency oscillations and for tuning the transformer to the desired beat frequency and a blocking condenser 29 is so connected in the lead connecting one terminal of the loop antenna 20 and the grid of tube 21 so as to prevent the intermediate frequency oscillations being impressed on the loop antenna and at the same 50 time so connected as to loosen the capacitative coupling through tube 21 of the circuit comprising inductance 24 and condenser 25 to the circuit comprising the loop 20 and condenser 22.

55 The secondary winding 26^s of beat frequency transformer 26 is connected across the grid and filament of tube 21, the connection to the grid of tube 21 being made between the grid and condenser 29. The plate filament circuit of tube 21 also comprises the primary winding 30^p of beat frequency transformer 30 and the B-battery B both 60 connected in series, the connection to the

plate of tube 21 not including the condenser 24'. The secondary winding 30^s of beat frequency transformer 30 is connected across the grid and filament of the three-element thermionic device or amplifying tube 31. 70

The plate-filament circuit of amplifying tube 31 comprises the primary winding 32^p of beat frequency transformer 32 and battery B_2 both connected in series and the condenser 41 shunting the primary winding 32^p 75 for properly tuning the plate-filament circuit to the desired beat frequency and for preventing any undesired high frequency oscillations passing through the primary winding 32^p of the transformer. 80

The secondary winding 32^s of beat frequency transformer 32 is connected in the grid-filament of the three-element detecting tube 33 and the usual grid condenser 34 shunted by a grid leak 35 is also included in 85 the grid-filament circuit.

The audio frequency oscillations appearing in the plate-filament circuit of detector tube 33 may be amplified by means of the audio frequency amplifying three-element 90 tubes 36 and 37 and the audio frequency transformer couplings 38 and 39. A sound reproduction device 40 may be connected in the plate-filament circuit of the last audio frequency amplifying tube 37 as shown. 95

The filaments of the various tubes may be supplied with heating current from a suitable source of power A and the currents in the individual filaments may be independently controlled by the various rheostats R . 100

The modification of my invention as shown by Fig. 1 functions as follows:

The loop antenna 20 is tuned by means of the variable condenser 22 to the incoming signal oscillations which are impressed on 105 the grid of tube 21. Tube 21 amplifies these radio frequency oscillations which are in turn impressed on the grid of the combined oscillating and detecting tube 23. By means of the tickler coil 27 and a proper adjustment of the variable condenser 25 the tube 23 is made to produce oscillations at a frequency equal to the frequency of the incoming signal oscillations minus or plus the desired beat frequency oscillations. Owing to 110 the fact that the inductance coil 24 and the variable condenser 25 are connected across the grid and filament of the tube 23, the incoming high frequency signal oscillations will be impressed on the grid of tube 23 and 115 no diminution but in fact magnification of potential on the grid will result even if the condenser 25 is adjusted to make the coupling comprising inductance 24 and condenser 25 resonant to the incoming signal oscillations. 120

The beat frequency oscillations appearing in the plate-filament circuit of tube 23 are now impressed on the grid and filament of tube 21 by means of the beat frequency 130

transformer 26, the condenser 28 bypassing all the undesired high frequency oscillations and also serving to tune the plate-filament circuit of tube 23 to the desired beat frequency oscillations.

The beat frequency oscillations considerably amplified by tube 21 will now flow through the plate filament circuit of tube 21 in which is included the primary winding 30^p of beat frequency transformer 30, the secondary winding 30^s of which impresses these beat frequency oscillations on the grid filament circuit of the beat frequency amplifying tube 31. The amplified beat frequency current oscillations flowing in the plate-filament circuit of tube 31 are then impressed on the grid-filament circuit of the intermediate frequency detecting tube 33. The audio frequency oscillations appearing in the plate-filament circuit of tube 33 are then further amplified by means of the audio frequency amplifying tubes 36 and 37 and the sound reproductive device 40 operates in response to the amplified audio frequency currents flowing in the plate-filament circuit of the last amplifying tube 37.

Referring to the Fig. 2, a variable tuning condenser 50 is connected across the terminals of the loop antenna 51. One terminal of the loop antenna 51 is connected to the grid of a three-element thermionic device or tube 52 through a blocking condenser 53 and the other terminal of the loop antenna is connected to the filament of the tube 52.

The plate-filament circuit of tube 52, which functions as a radio frequency amplifier, comprises the primary winding 54^p of beat frequency transformer 54 and plate battery B, both of which are connected in series with each other in the said plate-filament circuit. The plate of tube 52 is also connected to the grid of the combined oscillating and detecting tube 55 through the condenser 56 not included in the main plate-filament circuit of tube 52. This condenser prevents the impression of the B-battery voltage on the grid of tube 55. An inductance coil 57 is connected across the grid and filament of tube 55 and a variable tuning condenser 58 is connected in shunt with the inductance coil.

The plate-filament circuit of tube 55 comprises a tickler coil 59 inductively coupled to the inductance coil 57, the primary winding 60^p of a beat frequency transformer 60 and the plate battery B₁, all of which are connected in series. The secondary winding 60^s of beat frequency transformer 60 is connected across the grid and filament of tube 52, one of the connections being made on the grid side of the condenser 53. A condenser 61 is connected in shunt with the primary winding 60^p of beat frequency transformer 60 for preventing the passage of high frequency current oscillations through the windings of the transformer

and for tuning the plate filament circuit of the tube 55 for the intermediate or beat frequency oscillations.

The capacity of tube 52 together with that of condenser 56 is balanced by means of a lead, one extremity of which is connected to the grid of tube 52, in which is connected a balancing condenser 62 and an inductance coil 63 inductively coupled to the induction coil 57, the other extremity of the lead being connected to the filament extremity of inductance coil 57. The coils 57 and 63 are so arranged that the voltages therein are substantially 180° out of phase. The balancing of the capacity of tube 52 is thus accomplished thereby preventing any undesirable reaction between the loop antenna and the oscillating tube circuits and preventing radiation of oscillating tube energy from the loop antenna.

The secondary winding 54^s of beat frequency transformer 54 is connected across the grid and filament of the intermediate frequency amplifying tube 64, whose plate-filament circuit comprises the primary winding 65^p of beat frequency transformer 65 and plate battery B₂, both being connected in series. The secondary winding 65^s of transformer 65 is connected across the grid and filament of the audible frequency detector tube 66 having the usual grid condenser 67 and grid leak 68 connected to the grid in the usual manner as shown.

The audio frequency currents appearing in the plate-filament circuit of the detector tube 66 may be further amplified by means of the audio frequency amplifying tubes 69 and 70 suitably coupled by means of the audio frequency transformers 71 and 72. The plate-filament circuit of the last audio frequency amplifying tube 70 comprises the sound reproducing device 74 and plate battery B₅.

The filament of the various tubes may be supplied with heating currents from the common source of power A and individual control of the currents in the various filaments may be effected by means of the rheostats R.

This system functions in substantially the same way as the system shown in Fig. 1, the only difference being that the capacity of the radio frequency amplifier is balanced by means of the balancing condenser 62 and the coupler coil 63, which acts as an additional safeguard against the existence of undesirable oscillations in the loop circuit and undesirable reactions between the loop and oscillator circuits. The explanation given above for the operation of the system as shown by Fig. 1 is, therefore, thought to be sufficient as an explanation of the manner in which this embodiment of my invention functions.

While I have shown and described various

preferred modifications of my invention I wish it understood that I do not limit myself to said modifications but may employ many other embodiments which come within 5 the spirit and scope of my invention.

Having described my invention, what I claim is:

1. A superheterodyne receiving system comprising a tunable circuit adapted to have 10 signaling currents set up therein, a vacuum tube amplifier having its input circuit connected to said tunable circuit and its output circuit coupled to a combined oscillator and detector by means of a common 15 tunable circuit likewise serving to fix the frequency of oscillation of the generator and condensers connected in series in the amplifier circuits to loosen the inherent capacitative coupling through the amplifier tube to 20 prevent absorption of energy from the oscillator circuits by the first named tunable circuit.
2. A superheterodyne receiving system comprising a tunable circuit adapted to have 25 signaling currents set up therein, a radio frequency amplifier having its input circuit connected to said circuit with a condenser in series between said circuit and the amplifier, a combined oscillator and detector connected 30 to the output circuit of said amplifier by means of a common impedance for impressing the output of said amplifier on the input of said detector and for fixing the frequency 35 of oscillation of said oscillator and a second condenser connected between said amplifier and said impedance whereby the coupling between said impedance and said first named circuit will be loose enough to prevent absorption of energy by the latter from the former. 40
3. A superheterodyne receiving system

comprising a tunable circuit adapted to have 45 signaling currents set up therein, a radio frequency amplifier coupled thereto, the coupling comprising a condenser in series with the lead from the grid of said amplifier to 50 said tunable circuit, means for coupling said radio frequency amplifier to a combined oscillator and detector, means for reflexing the output of said combined detector and oscillator into said radio frequency amplifier, said last named means comprising a secondary coil of a transformer connected across 55 the grid and filament of said amplifier whereby detecting effects of the condenser in said grid circuit are eliminated.

4. A superheterodyne receiving system comprising a tunable loop antenna adapted to have 60 signaling currents set up therein, a radio frequency amplifier connected to said antenna, said connection comprising a condenser in series with the grid of said radio frequency amplifier, a combined oscillator and detector connected to the output circuit 65 of said amplifier by means of an impedance for fixing the frequency of oscillation of said oscillator and a second condenser connected between said amplifier and said impedance whereby the coupling between said impedance and said first named circuit will be loose enough to prevent absorption of energy 70 by the latter from the former, means for reflexing the output of the combined oscillator and detector means into the radio frequency amplifier, said means comprising a secondary coil of a transformer connected between 75 said first mentioned condenser and grid and to the filament of said radio frequency amplifier for preventing detecting effects of said condenser.

ARTHUR F. VAN DYCK.
